[57] CLAIM

The ornamental design for a toy rocking chair, substantially as shown and described.

DESCRIPTION

FIG. 1 is a front elevational view of a toy rocking chair showing my design;

FIG. 2 is a front perspective view; and

FIG. 3 is a side elevational view thereof.

The side of the toy rocking chair not shown is a mirror image of the side shown in FIG. 3.

FIG. 3
